US0D1091121S

(12) **United States Design Patent** (10) **Patent No.:** **US D1,091,121 S**
(45) **Date of Patent:** **** Sep. 2, 2025**

(54) **CARD HOLDER**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, Vienna (AT); **Clement Tissandier**, San Francisco, CA (US); **Eugene Antony Whang**, San Francisco, CA (US)

(73) Assignee: **Apple Inc.**, Cupertino, CA (US)

(**) Term: **15 Years**

(21) Appl. No.: **29/928,947**

(22) Filed: **Feb. 16, 2024**

Related U.S. Application Data

(63) Continuation of application No. 29/880,024, filed on Jul. 17, 2023, now Pat. No. Des. 1,014,964, which is

(57) **CLAIM**

The ornamental design for a card holder as shown and described.

DESCRIPTION

FIG. 1 is a top front perspective view of a card holder showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

(Continued)

FIG. 8 is a bottom view thereof.

The broken lines in the figures show portions of the card holder that form no part of the claimed design.

1 Claim, 6 Drawing Sheets

Related U.S. Application Data

a continuation of application No. 29/867,418, filed on Oct. 24, 2022, now Pat. No. Des. 994,330, which is a continuation of application No. 29/828,670, filed on Feb. 28, 2022, now Pat. No. Des. 967,625, which is a continuation of application No. 29/737,565, filed on Jun. 10, 2020, now Pat. No. Des. 944,520.
